M. OPPER
Take-Up Motion.

No. 57,177.

Patented Aug. 14, 1866.

UNITED STATES PATENT OFFICE.

MORRIS OPPER, OF NEW YORK, N. Y.

IMPROVEMENT IN LOOMS FOR WEAVING CLOTH WITH SWELLS OR GORES.

Specification forming part of Letters Patent No. 57,177, dated August 14, 1866.

To all whom it may concern:

Be it known that I, MORRIS OPPER, of the city, county, and State of New York, have invented a new and useful Improvement in the Take-Up Motion of Looms for Weaving Cloth with Swells or Gores; and I do hereby declare that the following is a full, clear, and exact description thereof, reference being had to the accompanying drawings, making part of this specification, in which—

Figure 1 is a plan, and Fig. 2 a longitudinal vertical section.

The same letters indicate like parts in both figures.

In weaving cloth with swells or gores—such, for instance, as required for making corsets—the weaving-in takes place at times across the entire width, and at other times across certain portions of the width, depending upon the extent, form, and location of the intended gores or swells. To accomplish this result in a power-loom the mechanism must operate on the woven cloth to take it up as woven on so much of the width as is being woven at any one time. When the weaving is taking place across the whole width the take-up mechanism must operate upon the whole width of the cloth to take it, and if the weaving is taking place on a quarter of the width, for instance, the take-up must operate on a corresponding part of the width and its operation be suspended on the other parts of the width.

In power-looms for this kind of weaving the parts of the width on which the weaving is to take place along the length is determined by the jacquard, and that mechanism also determines the corresponding part of the take-up which is to be active. There has been heretofore invented for this purpose what is denominated a "sectional" take-up—that is, a series of rollers mounted side by side on an arbor with a corresponding series of pressure-rollers, and each section of the take-up roller was actuated by a ratchet on a lever, all these ratchet-levers being connected with the jacquard by cords, and the sole duty of the jacquard was to select the levers of the sections required at any one operation of the loom to be operated and hold them in operation to be acted upon by the lay of the loom to make such rollers take up the corresponding sections of the loom.

My invention is of an improvement on such sectional take-up mechanism, by which I avoid the necessity of using a series of take-up rollers. I use the usual take-up roller, consisting of a single roller extending across the whole width of the cloth, and operated as usual by a ratchet movement at every beat of the lay, and I combine therewith a series of pressure or gripe rollers, which are borne down on the take-up roller by springs or equivalent means, and these are linked with levers so connected with the jacquard that when moved to the required position by the jacquard they will be acted upon by the lay to lift the pressure-rollers from the take-up roller, and thus liberate the cloth in the parts of the width where the weaving is suspended.

In the accompanying drawings, *a* represents a frame which is to be secured to the inside of the breast-beam of a loom. A take-up roller, *b*, of the usual or any suitable construction, is mounted in the said frame, and the shaft of this roller is provided with a ratchet-wheel, *c*, or other gearing, to be operated by a ratchet movement, as is usual in power-looms.

A series of right-angle levers, *d*, is mounted on a fulcrum-rod, *e*, and each of the said levers carries a roller, *f*, which is pressed upon the periphery of the take-up roller *b* by the tension of the spring *g*, so as to gripe the cloth with sufficient force to insure the taking up of the cloth by the motion of the take-up roller.

A series of vertical levers, *h*, are mounted on a fulcrum-rod, *i*, so that their upper arms can act on the levers *d* when required to lift the pressure-rollers *f* to liberate the cloth whenever the take-up operation is to be suspended; and to the lower arms of these levers *h* are jointed a series of rods, *j*, held up by cords *k*, which extend up to the jacquard, there being one such cord, rod, and lever for each pressure-roller *f*.

The rods *j* are provided with a projecting shoulder, *l*, and on the lay of the loom, and attached to the swords thereof, there is a bar, *m*, to strike against the shoulders of the rods. When the jacquard lifts any of the rods *j* to the position represented by dotted lines the bar *m* on the lay will clear them, so that the corresponding rollers *f* will make the required pressure on the cloth and cause the take-up

roller to take up corresponding portions of the width of the cloth; but such of the rods as are not lifted by the jacquard will be struck by the bar *m* on the forward beat of the lay, thereby lifting the corresponding rollers *f*, which will cause the take-up operation to be suspended on corresponding parts of the width of the cloth. In this way it will be seen that the cloth can be taken up on any part of its width, as may be determined by the mounting of the jacquard, without the necessity of a sectional take-up roller.

What I claim as my invention, and desire to secure by Letters Patent, is—

The series of pressure-rollers operated by the lay of the loom, substantially as described, and controlled by the jacquard or equivalent therefor, in combination with the take-up roller, substantially as and for the purpose specified.

MORRIS OPPER.
